UNITED STATES PATENT OFFICE.

CYRUS EVERE, OF NEW YORK, N. Y., AND JOSEPH H. DICKINSON, OF MONTCLAIR, NEW JERSEY.

LOGGING-ENGINE.

1,103,135.

Specification of Letters Patent. Patented July 14, 1914.

Application filed June 29, 1910. Serial No. 569,431.

To all whom it may concern:

Be it known that we, CYRUS EVERE, a citizen of the United States, and a resident of New York city, borough of Brooklyn, in 5 the county of Kings and State of New York, and JOSEPH H. DICKINSON, a citizen of the United States, and a resident of Montclair, in the county of Essex and State of New Jersey, respectively, have invented 10 a certain new and useful Improvement in Logging-Engines, of which the following is a specification.

Our invention relates broadly and generally to new and useful improvements in logging engines, and more particularly to that 15 character or type adapted for use in connection with an inhaul and outhaul cable-way, which usually includes a log pulling line operable to haul logs from a remote 20 point to a point in proximity to the engine, and an outhauling means for outhauling the log attaching means to a point from which the logs are to be inhaled.

The primary object of the present invention 25 is to construct an improved engine which will be simple in construction, in which all of the line operating drums will be located compactly within the supporting frame, and in which the driving means for 30 the drums will be so arranged and operable in such a manner that all of the lines operated upon and controlled by the drums will come off the top of the drums, *i. e.*, be 35 tangential to the circumferential surface of the top portion of the drums.

The invention consists in the improved 40 construction to be fully described herein-after and the novelty of which will be particularly pointed out and distinctly claimed.

We have fully illustrated our invention 45 in the accompanying drawings to be taken as a part of this specification and wherein—

Figure 1 is a view in side elevation, partly 50 in section, of a construction embodying our invention; Fig. 2 is a plan view, partly in section, of the improved engine; Fig. 3 is a section on the line 3—3 of Fig. 2.

Referring to the drawings by characters 55 of reference, A designates generally a substantial framework of proper dimensions and strength to suit it for the purposes for which it is employed, said framework being adapted to support the several parts of the improved logging engine. While the exact

design of this frame need not be confined 55 to any particular form we prefer that the same be rectangular in general contour, the same including longitudinal side members 1, 2 joined at one end by an end cross piece 3, and at the other end by a platform 4, 60 the latter constituting a support for a steam generating boiler B, and engine cylinders C, the latter being located on opposite sides of the boiler. The space bounded by said platform, the side pieces 1, 2 and the end 65 piece 3, is longitudinally divided by a central member 5 connecting said platform and end piece, whereby the frame between the side members is divided into two spaces 70 in which the rope operating drums are located, as will be presently described.

In suitable bearings 6, 6, 6 mounted in the side pieces 12 and the center member 5, in front of the boiler is a transversely arranged horizontal driving shaft 7, on each 75 end of which outside the main frame, is mounted a crank disk 8, carrying a crank pin 9, each connected by a pitman 10 with the piston rod 11 of a piston of one of the engine cylinders C. On the power shaft 80 adjacent each of the crank disks is an eccentric 12 for operating the valve rod 13 for the valve 14 of the engine on that side of the frame.

The engine parts and driving connections 85 just described form no part of our present invention, and are shown and described merely in order that the operation of the complete apparatus will be more easily understood.

On the driving shaft 7 adjacent the central frame member 5 is fixed a driving pinion 15, which meshes with a driven gear 16, which is keyed on a horizontal shaft 17, having bearing in alining bearings 18, at 95 the upper portions of pillars 19, on the side and center members of the frame, said shaft 17 being located in a horizontal plane above the driving shaft and in a vertical plane forward of said shaft. This gear 16 is provided in one of its faces with an annular friction element 20, preferably in the form of wood friction blocks having outer inclined surfaces 20°, and mounted on the shaft 17 on the same side of the center member as the 100 said gear 16, is a rope drum 21, having end flanges 22, the one adjacent the gear 16 being provided with an annular friction mem-

ber 23, having an inclined face 24 adapted to coöperate with the inclined face of the friction element on the gear 16. This drum is mounted for movement longitudinally of the shaft 17, and for this purpose we employ a thrust mechanism consisting of a cross-piece 25 located in a slot 26 in the shaft 17, a thrust collar 27 being arranged between the cross-piece and the drum, and both the 5 cross-piece and the collar being housed in a recess in the end of the drum, as shown in Fig. 3. Extending longitudinally through the shaft is a thrust pin 28 which is engaged by a thrust screw 29, threaded in a bracket 30 in the frame, and connected to this screw 29, is an arm 31, which is in turn connected by a link 32 with an arm 33 on an operating shaft 34 extending horizontally across the frame and having an arm 35 by which it is 10 operated to turn said screw to move the drum toward the gear to frictionally connect the same thereto. The drum is moved in the opposite direction to disconnect it from the gear by rotating the screw to relieve its pressure upon the drum, and engaging the end of the screw is an arm 36 on a slide rod 37, mounted in an aperture in the side frame of the machine, and carrying at its inner end a yoke 38 seated in a groove 39 formed in a flange on the end of the drum, the arrangement being such that when the screw is moved outward to relieve the friction, the movement is transmitted to the drum to positively move the same to break 15 the frictional engagement between the drum and gear. The drum 21 when coupled to the driven gear 16 is adapted to take up an outhaul rope or that part of a cableway serving to outhaul the logging line, and is disconnected from the said gear while the in-hauling operation is taking place. A suitable shoe brake 21^a is arranged in engagement with the outer cylindrical surface of the clutch element 24, pivoted to an arm 21^b, 20 on a rock shaft 21^c mounted on the frame and having a lever arm 21^d, engaged by an arm 21^e on an operating rock shaft 21^f also mounted on the frame, and operable by a foot lever 21^g. 25

50 Mounted on the shaft 17 in the frame space on the opposite side of the center member from that containing the drum 21, is a gear 40 keyed to the shaft, and arranged in mesh with a pinion 41 keyed to a shaft 42 30 located directly beneath the shaft 17 and having its respective ends journaled in bearings 43 in the pillars 19 of the center member and side frame, the inner end of said shaft terminating at the center member. 35 This pinion 41 in turn meshes with a large gear 44, keyed to a horizontally disposed shaft 45, journaled in bearings 46 in the forward part of the center and side frame members, and at a point thereon adjacent 40 the base of the pillars 19. This gear 44 is

provided with an annular friction element 46, in the form of a wood annulus having an inclined outer face 47.

Keyed to the shaft 45 in the frame space containing the pinions 40, 42 and gear 44, 45 is a drum 48 having end flanges 49, the outer face of the one nearest the said gear 44 having a clutch ring 50 formed with an inner inclined face 51 to engage the inclined face 47 on the gear 44. This drum is movable 50 longitudinally of its shaft by a suitable thrust mechanism 51 to place the said friction clutch elements in and out of engagement. This drum is adapted to have wound thereon the inhaul rope of a logging system, and operates when coupled to the driving gear 44 to take up said rope to inhaul a load. Journaled in the front part of the frame is a rock shaft 52 having an arm 53 to which is connected a brake shoe 54 which 55 engages the outer face of the element 50 on the drum, said brake being operable to retard or control the rotation of the drum when disconnected from the gear 44. The end of the shaft 52 which projects outside the 60 frame, as shown in Fig. 2, has a foot lever 52^a by means of which the brake is operated.

Mounted within the same frame space as that containing the drum 21, and keyed to the shaft 45 is a friction element 55, and 65 loosely mounted on said shaft in said space is a loading drum 56 having an annular friction surface 57, to coöperate with said element 55, said drum being longitudinally movable of the shaft by means of thrust 70 means 58 to place it in engagement with said element 55 to drive said drum.

Journaled in the frame in longitudinal alignment with the shaft 52, is a second rock shaft 59 having an arm 60, connected by a 75 link 61 with one arm 62 of a bell-crank lever mounted on a shaft 63, the opposite arm 64 which is connected to one end of a band brake 65, acting on the flange 57, the opposite end of said band being anchored on the 80 frame as shown at 66. The outer end of the shaft 59 has thereon a foot lever 67, which it will be seen is on the opposite side of the machine from the levers which control the operation of the drums 21 and 48, as 85 is also the thrust means 58. The purpose of this arrangement is to permit independent operation of the loading drum by an operator other than the one controlling the in-haul and outhaul drums, while the log hauling 90 operation is going on.

The throttle valve for the engine cylinders is shown at 68, the valve rod 69 being horizontally disposed and carried to a point adjacent the operating levers for the inhaul 95 and outhaul where it is provided with a hand lever 70, the arrangement being such as to permit convenient operation of said valve by the machine operator conducting the log hauling without leaving his station. 100

The operation of the construction set forth is as follows, it first being understood that the inhaul rope 71 of the cableway is wound upon the drum 48 and the outhaul lead 72 of the cableway upon the drum 21: Presuming now that the inhaul line is drawn in so that the tongs or other log engaging means (not shown) are adjacent the machine, the operator disconnects the drum 48 from the gear 44, and connects the drum 21 with the gear 16, and then operates the throttle valve to admit steam to the engine cylinders, which operate to revolve the power shaft 7 in the direction of the arrow in Fig. 1. The power shaft 7 being set in motion it serves through the pinion 15 and gear 16 to revolve the drum 21 to take up the outhaul line 72 which acts on the outhaul line 71 to outhaul the log engaging means to a point where the logs are to be connected to the inhaul line. During this operation the brake 54 is operable to retard and control the revolution of the inhaul drum to maintain the hauling line taut. When the inhaul line is sufficiently out-hauled, the operator disconnects the outhaul drum 21 from its driving gear 16 and applies the brake 21^a to prevent overrunning of the drum, and couples the inhaul drum 48 by means of the friction clutch parts 46^a, 50 to the driving gear 44. The inhaul drum then operates to take up the inhaul rope to draw in the load, the outhaul drum 21 running free, under control of its brake, to pay out the outhaul line. During the operation above stated, the loading drum may be operated to perform the loading of the logs by the loading line 73 wound on said drum 56, entirely without regard to the inhauling and outhauling of the logging system, the result being that both the hauling operation and the loading operation may be conveniently and effectively carried on by the same machine, run from the same source of power, but entirely independently of each other and by independent operators.

By the construction and arrangement shown and described it is seen that all of the drums for performing all of the logging operations are included within a single struc-

ture, and within the supporting frame. It will also be seen that by the arrangement of gearing we are enabled to so drive all of the drums that the ropes wound on the latter all pass off tangential to the upper surface 55 thereof.

Having thus described our invention, what we claim as new and desire to secure by Letters Patent is:

1. In a logging engine, in combination, a frame comprising side members and an intermediate member, a driving shaft and a drum shaft geared thereto journaled in the said side members and intermediate member, a drum on the drum shaft between one side member and the intermediate member, a counter shaft geared to said drum shaft and located on the opposite side of the intermediate member from the said drum, a second drum shaft geared to the counter shaft, and a drum on the second drum shaft on the opposite side of the intermediate member from the first named drum.

2. A logging engine comprising side and intermediate frame members, a power shaft journaled in said members and carrying a pinion, a drum shaft in advance of the power shaft and journaled in the side frame members, and having a gear fixed thereto meshing with said pinion, a rope drum on said shaft, said gear and drum having co-operable clutch members, a pinion fixed to said drum shaft, a counter shaft arranged beneath the said drum shaft and having a pinion meshing with the second-named pinion, a drum shaft in advance of said first drum shaft and having a driving gear fixed thereto, a drum loosely mounted on said second drum shaft, said last-named driving gear and drum having co-operable clutch members.

In testimony whereof we have signed our names to this specification in the presence of two subscribing witnesses.

CYRUS EVERE.
JOSEPH H. DICKINSON.

Correction in Letters Patent No. 1,103,135.

It is hereby certified that in Letters Patent No. 1,103,135, granted July 14, 1914, upon the application of Cyrus Evers, of New York, N. Y., and Joseph H. Dickinson, of Montclair, New Jersey, for an improvement in "Logging-Engines," an error appears in the printed specification requiring correction as follows: Page 2, line 77, for the reference-numeral "51" read 51^a ; and that the said Letters Patent should be read with this correction therein that the same may conform to the record of the case in the Patent Office.

Signed and sealed this 11th day of August, A. D., 1914.

[SEAL.]

J. T. NEWTON,

Acting Commissioner of Patents.
